Attorney.

UNITED STATES PATENT OFFICE.

WILLIAM C. EHRENFELD, OF FLEMINGTON, NEW JERSEY.

TUBE CONNECTING AND VULCANIZING MEANS.

1,364,985.

Specification of Letters Patent. Patented Jan. 11, 1921.

Application filed August 21, 1920. Serial No. 404,974.

To all whom it may concern:

Be it known that I, WILLIAM C. EHRENFELD, a citizen of the United States, residing in Flemington, Hunterdon county, New Jersey, have invented certain new and useful Improvements in Tube Connecting and Vulcanizing Means, of which the following is a specification.

My invention relates to means employed for splicing, or connecting into continuous lengths, the inner tube of automobile tires, and one object of my invention is to provide an improved form of vulcanizer for curing or effecting the connection between the open ends of a tube.

A further object of my invention is to provide improved means of connecting the halves of the vulcanizing chest when the same is in the active position.

20 A further object of my invention is to provide improved means for automatically opening the vulcanizing chest when the operation is completed and the connecting means have been released, and a still further 25 object is to provide an improved form of sleeve receiving the ends of the tube to be connected, and the means for mounting the same in the vulcanizing chest.

These and other features of my invention, 30 including the necessary accessories, are more fully described hereinafter; reference being had to the accompanying drawings, in which:

Figure 1, is a view in elevation of my improved vulcanizing structure in the closed position.

Fig. 2, is a plan view of one half of one of the tube-receiving sleeves.

Fig. 3, is a cross sectional view of the complete sleeve in position in the vulcanizing chest, and

Fig. 4, is a view illustrating a detail of my invention.

As is well known, the inner continuous 45 tubes of automobile tires are made from rubber tubing out to the desired lengths; the open ends of which must be joined to form the continuous tubular structure. In practice, such lengths are straight in some 50 instances, and in other instances they are curved approximately to the contour that the continuous tubes will assume when disposed in the shoe or casing of an automobile tire. The ends of the tubular lengths must

be joined to form a continuous tube, and my 55 invention comprises an improved form of vulcanizing chest; locking means therefor; a sleeve receiving the mandrel over which the ends of the tube are stretched preparatory to being placed in said vulcanizing 60 chest, and accessories necessary in operating the structure.

In the drawings 1, represents a base upon which the vulcanizing chest is mounted. This base may have an overhanging upper 65 portion 2 to which the lower half 3, of the vulcanizing chest is secured, or, if desired, this section may be formed integral therewith. Hinged to this section 3, is the upper section 4 of the vulcanizing chest, and this 70 hinged connection may have a plain pivot pin 5, or, in lieu thereof I may employ an eccentric pin as described hereinafter.

At the front end of the vulcanizing chest, the lower section 3 is provided with an end 75 projection 6, apertured at 7, for the reception of the arms 8 of a yoke-strap; the upper looped end 9 of which may be caught over a hooked projection 10, carried at the front end of the upper section 4 of the chest. 80 The lower ends of the arms 8 carry an eccentric member 11, having end projections 12 apertured for the passage of these arms 8, and the latter carry nuts 13 whereby the position of these arms with respect to this eccentric 85 block may be adjusted.

When the sections of the vulcanizing chest are connected together, the eccentric block 11, lies under the projection 6, and by turning said block, a camming action is effected 90 and the yoke member is caused to tightly clamp the upper and lower sections of the vulcanizing chest together. To turn the eccentric block, it may be provided with a recess 14, and a rod 15, of suitable size and 95 character may be employed for this purpose. When not in use, this rod may be placed in a socket 16 formed for the purpose in the top of the upper half of the vulcanizing chest. If desired, a boss 17 may 100 be provided in which the socket may be formed.

The upper section is preferably provided with an extension arm 18, and one end of a spring 19 may be connected at 20, to the 105 outer end of this extension arm, with its opposite end attached at 21 to a bracket 22 carried by the standard portion of the base,

so that when the sections are opened, after the connecting means are released, the upper section will be raised automatically so as to permit insertion and removal of the sleeves 5 and the tube ends carried thereby.

The upper face of the lower half of the vulcanizing chest may be provided with a rib or projection 23 for engagement with a recess 24 in the meeting face of the upper 10 half of the chest, so as to insure proper registry when the upper and lower sections are brought together.

The tube ends to be connected together are held between the registering halves of sleeves 25, which are disposed in recesses 26 formed in the upper and lower sections of the vulcanizing chest. One of these sleeve sections is clearly shown in Fig. 2, and each half is a duplicate of the other. These half 20 sleeves may be held in the recesses of the upper and lower sections of the vulcanizing chest, with their meeting faces on the line of division between said sections, by means of lips 27 carried by the chest sections, which 25 enter recesses or grooves 28 formed at the edges of the sleeve sections.

Each sleeve section is provided with a flange 30 at one end to limit endwise movement of the same with respect to the sections 30 of the chest, and these flanges 30 are additionally provided with projecting members 31 to limit endwise movement of the mandrels when the latter are inserted in the sleeves and between which and said sleeves 35 the tube ends are disposed. These mandrels, and the manner of operating the same are fully described in my Patent 1,314,256, dated August 26, 1919. The sleeve sections are provided with an internal wall of two diameters as in my patent referred to; end portions 32 and 32^a, of the same diameters, with a portion 32^b between the same of less diameter and having beveled or sloping portions 33 and 33^a continuous with and connecting 40 the several surfaces 32, 32^a and 32^b.

I may provide the vulcanizing structure with a pin or projection 35, upon which the mandrel key 36 may be hung, as indicated in Fig. 1.

50 In lieu of the plain pivot pin 5, shown in Fig. 1, I may employ a pin having an eccentric portion so that the hinged connection may be tightened when the sections of the chest are clamped together, as shown in Fig.

55 4. In this instance the lug of the lower section may receive the eccentric portion 38 of the pin, while the lugs of the upper section receive the portions 39, upon which said upper section may swing when the sections of 60 the chest are opened. One of the portions 39 may be provided with a projection 40, having an aperture 41, so that a bar may be inserted therein to give the pivot pin a slight turn after the halves of the vulcanized chest 65 are in registry so that the sleeve sections dis-

posed between the same may be more tightly clamped between the sections of the vulcanizing chest.

The sections 3 and 4 of the vulcanizing chest receive a heating medium and this may 70 be introduced via pipes indicated at 42 and 43.

I claim:

1. In a vulcanizing chest, the combination of upper and lower sections having registering recesses, half sleeve sections fitting said recesses, a clamping yoke for the front ends of said chest sections; said clamping yoke being connected to the lower section and being adapted for engagement with a projecting hook carried by the upper section, and a rotatable member having an eccentric portion carried by the lower end of said clamping yoke and adapted to underlie the lower chest section whereby upon turning said rotatable member, the clamping yoke will be tightened to clamp the chest sections together. 75 80 85

2. In a vulcanizing chest, the combination of upper and lower sections having registering recesses, half sleeve sections fitting said recesses, means for securing the respective halves of said sleeve sections to the several chest sections, a clamping yoke for the front ends of said chest sections; said clamping yoke being connected to one of the sections and being adapted for engagement with a projecting hook carried by the other section, and a rotatable member having an eccentric portion carried by the face end of said clamping yoke and adapted to engage one of the chest sections whereby upon turning said rotatable member, the clamping yoke will be tightened to clamp together the chest sections and the registering half sleeves carried thereby. 90 95 100 105

3. In a vulcanizing chest, the combination of upper and lower sections having registering recesses, half sleeve sections fitting said recesses, projecting lips carried by the recesses of the chest sections longitudinally of the same and adapted to engage recesses in the longitudinal edges of the sleeve sections whereby the latter may be held in place, and means for clamping said chest sections together. 110 115

4. In a vulcanizing chest, the combination of upper and lower sections having registering recesses, half sleeve sections fitting said recesses, projecting lips carried by the recesses of the chest sections adapted to engage recesses in the edges of the sleeve sections whereby the latter may be held in place, a clamping yoke for the front ends of said chest sections, said clamping yoke being connected to one of the sections and being adapted for engagement with a projecting hook carried by the other section, and a rotatable member having an eccentric portion carried by the face end of said clamping 120 125 130 135 140 145 150 155 160 165 170 175 180

yoke and adapted to engage one of the chest sections whereby upon turning said rotatable member, the clamping yoke will be tightened to clamp the chest sections together.

5. In a vulcanizing chest, the combination of upper and lower sections having registering recesses, half sleeve sections fitting said recesses, means for securing the sleeve sections in place, means for clamping said chest sections together, an arm carried by the upper section and projecting beyond the hinged connection for the same, and a spring connected to said arm and serving to automatically open the vulcanizing chest when the clamping means are released.

6. In a vulcanizing chest, the combination of upper and lower sections having registering recesses, half sleeve sections fitting said recesses, means for securing the sleeve sections in place, a clamping yoke for the front ends of said chest sections, an arm carried by the upper section and projecting beyond the hinged connection for the same, and a spring connected to said arm and serving to automatically open the vulcanizing chest when the clamping yoke is released.

7. In a structure such as set forth in claim 1, a lug carried by one section of the vulcanizing chest and adapted to enter a recess in the other section whereby the parts may be held in lateral registry.

8. In a structure such as set forth in claim 1, a lug carried by the lower section of the vulcanizing chest, and adapted to enter a recess in the upper section whereby the parts may be held in lateral registry.

9. In a structure such as set forth in claim 1, a clamping yoke connected to one section of the chest and adapted to engage a hooked projection carried by the other section whereby the parts of the chest may be held together, and camming means for tightening said clamping yoke.

10. In a structure such as set forth in claim 1, a clamping yoke connected to the lower section of the chest and adapted to engage a hooked projection carried by the upper section whereby the parts of the chest may be held together, and camming means for tightening said clamping yoke.

11. In a vulcanizing chest for connecting the ends of tubes, a pair of separable sections, a hinged connection therefor having an eccentric pin, clamping means for the front end of said chest, and an eccentric member adapted to apply pressure to said clamping means when said sections are brought together.

12. In a vulcanizing chest for connecting the ends of tubes, a pair of separable sections, a hinged connection therefor having an eccentric pin, clamping means for the front end of said chest, an eccentric member adapted to apply pressure to said clamping means when said sections are brought together and registering half sleeve sections carried by said separable chest sections.

13. In a structure such as set forth in claim 1, a pair of separable chests having registering recesses receiving tube connecting sleeves, a hinged connection for said chests, releasable clamping means at one end of said chests, and means for automatically opening the sections of the chest when such clamping means are released.

14. In a structure such as set forth in claim 1, a pair of separable chests having registering recesses receiving tube connecting sleeves hinged together, releasable clamping means for the front end of said chests, and a spring for automatically separating the chest sections when such clamping means are released.

In witness whereof I have signed this specification.

WILLIAM C. EHRENFELD.
